Primary Examiner—Wallace R. Burke*Assistant Examiner*—H. Bayham*Attorney, Agent, or Firm*—Robert A. Seemann**[57] CLAIM**

The ornamental design for a rebar spacer, as shown and described.

DESCRIPTION

FIG. 1 is an end view of a rebar spacer showing my new design;

FIG. 2 is a side view thereof;

FIG. 3 is a perspective view thereof;

FIG. 4 is a top plan view thereof;

FIG. 5 is a 45 degree rotated side view thereof; and,

FIG. 6 is a right side, end perspective view thereof. The broken line showing of reinforcement bar is for illustrative purposes only and forms no part of the claimed design.

FIG. 1

FIG. 2

FIG. 3

FIG. 4
